UNITED STATES PATENT OFFICE.

EMIL KUHNKE, OF LEVERKUSEN, GERMANY, ASSIGNOR TO SYNTHETIC PATENTS CO., INC., OF NEW YORK, N. Y., A CORPORATION OF NEW YORK.

EVAPORATING APPARATUS.

1,126,491.

Specification of Letters Patent.

Patented Jan. 26, 1915.

Application filed August 14, 1913. Serial No. 784,774.

To all whom it may concern:

Be it known that I, EMIL KUHNKE, engineer, citizen of the German Empire, residing at Leverkusen, near Cologne, Germany, have invented new and useful Improvements in Evaporating Apparatus, of which the following is a specification.

In the evaporation of liquids the depth of the body or column of liquid undergoing evaporation has marked influence on the amount of evaporation and on the consumption of steam or other heating agent. This is because the liquid near the bottom of the body or column is under a higher pressure than that near the top, due to the head of liquid above it, and boils at a correspondingly higher temperature. As a result when steam at a uniform temperature is used in heating the body of liquid, the temperature difference between the steam and the liquid decreases with the increase in pressure and in boiling point of the liquid. This condition is particularly disadvantageous in high vacuum work, since, for example, in a body 20 of water 1 meter deep maintained under a vacuum of 700 mm., the difference between the boiling points of the upper and lower layers of water amounts to about 15° C. In the evaporating apparatus of the prior art 25 little attention has been paid to these unfavorable influences.

The apparatus of the present invention is designed to overcome the above-mentioned disadvantages, and enables a uniform depth 30 of liquid to be maintained, this depth not exceeding the diameter of the boiler tubes employed.

The invention will be now more particularly pointed out and described in connection with the illustration thereof shown in the accompanying drawings, in which,—

Figure 1 shows a central vertical section of the evaporating apparatus. Fig. 2 shows a vertical section on the lines B—B, Fig. 1, 45 and Fig. 3 is an enlarged detail view showing the arrangement of the pockets and connections.

In the embodiment of the invention illustrated, the heating chamber *a* is shown as 50 having two headers or tube plates *b* and *b'* into which are welded the boiler tubes *c* which cross each other in pairs. On the outside of the tube plates or headers are arranged pockets *d* and *d'*, each pocket being 55 opposite a series of pairs of crossed tubes,

so that one tube of each pair leads from near the bottom of a pocket on one tube plate to a pocket on the other tube plate at a slightly higher level. Overflow pipes *e* are provided from one pocket to the next, 60 the ends of these pipes being arranged on a level with the highest point in the ends of the lower tubes. The heating chamber *a* is provided with a steam inlet connection *f* and an outlet *g* for the water of condensation. 65 The pockets *d* are supplied by means of an inlet pipe *h* and the evaporated liquid escapes from the pockets into the surrounding space from which it is conveyed through suitable openings to the desired receptacle. 70

In the operation of the apparatus the heating steam enters at *f* and surrounds and heats the tubes *c*, the condensed water being drawn off at *g*. The liquid to be evaporated enters at *h* into the top pocket *d* 75 and then into the ends of the lower tubes. From this pocket the liquid overflows into the next pocket, and so on, when the level reaches the top of the overflow pipe *e*. This level is such that the liquid fills the ends of 80 the lower tubes and tends to maintain this constant level in the tubes. The evaporated liquid passes to the remote and slightly higher ends of the tubes in the other header and the liquid carried with the vapors is 85 discharged into the corresponding pocket on this other header, from which the operation is repeated through the other series of tubes into the first header. The surging of the liquid and vapors in the crossed tubes, and 90 the carrying of liquid by the vapors results in forcing liquid into the remote pockets in which the same operation takes place. The head of liquid, however, is maintained constant by the overflow pipes. In order to 95 prevent the liquid or mixed liquid and vapors from oscillating back and forth in the inclined boiler tubes, the lower ends of each series have angular sleeves *i* screwed on them with openings therein considerably 100 smaller in size than the inside of the tubes. Any tendency toward back flow through these sleeves and reduced openings is prevented or minimized and the surging of the liquid or mixed liquid and vapors permitted 105 only in the direction of the pockets at the upper and outlet ends of the tubes. As a result of this arrangement and operation the liquid head in all the pockets and tubes is maintained practically constant, so that uni- 110

form evaporation at a constant temperature is permitted.

I claim:—

1. An evaporating apparatus comprising a boiler having a heating chamber provided with a header at each end, a series of tubes arranged between said headers at a slight inclination, pockets on said headers at the ends of said pipes, and means for maintaining the liquid in said pockets at a constant level.
2. An evaporating apparatus comprising a boiler having a heating chamber provided with a header at each end, a plurality of superposed series of tubes arranged between said headers at a slight inclination, pockets on said headers at the ends of each of said series, and overflows arranged from each pocket to the next below arranged to maintain the liquid in said pockets at a constant level.
3. An evaporating apparatus comprising a boiler having a heating chamber provided with a header at each end, pockets on the outside of said headers, two series of crossed tubes arranged in pairs each of which leads

from a pocket on one header to a higher level in a corresponding pocket on the other header, and means for maintaining a constant level of liquid in said pockets.

4. An evaporating apparatus comprising a boiler having a heating chamber provided with a header at each end, a series of superposed pockets on the outside of each header, two series of crossed tubes arranged in pairs and extending from a pocket on one header to a corresponding pocket on the other, one tube of each pair leading from a lower level of one pocket to a higher level of the other, means for supplying said pockets with liquid to be evaporated, and overflows from each pocket to the next arranged to maintain in the pockets a constant level of liquid even with the tops of the lower ends of said tubes.

In testimony whereof I have hereunto set my hand in the presence of two subscribing witnesses.

EMIL KUHNKE. [L.S.]
